CLEANING MACHINE

Howard J. Clifford, Phoenix, Ariz., Joe A. Dugger, Rte. 1, Box 90-A, Brawley, Calif. 92227, and Dick L. French, El Centro, Calif.; said Clifford and said French assignors to said Dugger

Filed June 21, 1966, Ser. No. 560,378
9 Claims. (Cl. 19—200)

This invention relates to a cleaning machine, and more particularly, to a cleaning machine particularly adapted for cleaning cotton for removing the motes therefrom and a machine which may be particularly adapted for cleaning cotton containing motes and which cotton is generally a waste by-product of cotton ginning operations.

It has generally been a problem to salvage cotton containing motes and particularly that cotton which is a by-product of cotton ginning operations. Cotton gins are generally unable to remove all of the motes from cotton and consequently, most gins have a substantial amount of cotton containing motes which are generally very difficult to remove from the cotton, consequently, such cotton containing motes is of a very low grade.

Accordingly, it is an object of the present invention to provide a cleaning machine which will remove a very high percentage of the motes from cotton and particularly from that cotton which is generally a by-product of cotton ginning operations.

Another object of the invention is to provide a cleaning machine which is capable of removing motes from various fibers.

Another object of the invention is to provide a cotton cleaning machine which is very simple and economical of construction, efficient in operation and which is also very durable.

Another object of the invention is to a novel cotton cleaning machine comprising a pair of counter-rotating rotors which operate at high speed above arcuate rows of bars and wherein cotton containing motes is advanced longitudinally of said rotors by means disposed at a helical angle to the axes of said rotors, such that the material, such as motes, contained in cotton fibers or the like, is moved at high speed by the rotors and over the grade bars and advanced through several helical cycles longitudinally along the rotors, whereby the motes having a substantially higher specific gravity than the fibers are centrifugally dispelled through the grade bars to a trash receiving plenum and whereby concurrently the high velocity beating action of beater members of the rotors tends to break up the cotton so as to relieve the motes therefrom and to enable these motes to pass between grill bars and into the trash plenum.

Another object of the invention is to provide a cleaning machine having novel counter-rotating beater rotors in combination with rows of grate bars adjacent thereto and novel means adjacent to the rotors for helically advancing the cotton and motes or other fibers longitudinally along the rotors for beating the cotton and for subjecting it to a plurality of helical cycles around the rotors and between the rotors, as they counter-rotate to each other.

An additional object of the present invention is to provide a cotton cleaner, wherein a plurality of counter-rotating rotors are disposed in a horizontally axial position and in spaced parallel relationship to each other and housed such that they receive cotton motes at locations in which the peripheries of the rotors rotate toward each other and wherein helical advancing means in the housing is adjustable to various helical angles for controlling the rate at which cotton and motes may pass longitudinally of the axes of the rotors.

Further objects and advantages of the present invention

2

may be apparent from the following specification, appended claims and accompanying drawings, in which:

FIG. 1 is a side elevational view of a cleaning machine in accordance with the present invention;

FIG. 2 is an enlarged fragmentary side elevational view of the cleaning machine of the invention, showing parts and portions thereof broken away and in section to amplify the illustration;

FIG. 3 is a sectional view taken from the line 3—3 of FIG. 2;

FIG. 4 is an enlarged fragmentary sectional view taken from the line 4—4 of FIG. 2;

FIG. 5 is an enlarged fragmentary sectional view taken from the line 5—5 of FIG. 4;

FIG. 6 is a fragmentary sectional view taken from the line 6—6 of FIG. 1; and

FIG. 7 is an enlarged fragmentary sectional view taken from the line 7—7 of FIG. 3, showing a modification of the structure shown in FIG. 3; the section line 7—7 being disposed only to show location of the structure of FIG. 3 which is modified in accordance with the showing of FIG. 7.

As shown in FIGS. 1, 2 and 3 of the drawings, the cleaning machine of the invention is provided with a housing 10 supported on legs 12. The housing 10 is provided with a generally vertically directed inlet 14 disposed to receive material at the top of the housing 10 and the housing 10 is provided with a downwardly directed outlet 16 adapted to deliver cleaned fibers downwardly out of the housing 10.

The housing 10 is also provided with a downwardly directed trash receiving plenum 18, all as will be herein-after described in detail.

Communicating with the outlet 16 is a centrifugal blower 20 or any other suitable source of vacuum tending to cause air to flow outwardly through the outlet 16 in a downward direction, as indicated by arrows 22 and outward in a direction indicated by arrows 24, as shown in FIG. 3 of the drawings. Likewise, a blower or other suitable source of vacuum, designated 26 is connected to the plenum 18 at a lower horizontal conduit portion 28 thereof. The blower 26 is disposed to produce air flow in a direction of an arrow 30 to carry trash away from the interior of the trash plenum 18.

It will be noted that the blowers 20 and 26 are only used for conveying the cleaned cotton and the trash from the machine, but are not used as a source of vacuum to effect operation of the machine, all as will be hereinafter described in detail.

As shown in FIGS. 2 and 3 of the drawings, rotors 32 and 34 are carried on respective shafts 36 and 38, these shafts being axially disposed in spaced parallel relationship with each other and operable horizontally. The rotors 32 and 34 are cylindrical in cross-section and each rotor is provided with a plurality of radially extending beaters, the rotor 32 having beaters 40 and the rotor 34 having beaters 42. These beaters 40 and 42 are generally vane-shaped, as shown in FIGS. 2 and 3 of the drawings, and may have opposite sides normal to the axes of the shafts 36 and 38 or in a modified structure, as shown in FIG. 7, the vanes may be designated 44 and may have opposite sides 46 and 48 disposed at an acute angle to the rotor axis designated 50 in FIG. 7, which axis may correspond to the axes of the shafts 36 and 38 in the structure shown in FIG. 3.

The helical angle of the beaters 44 of the modified structure of the invention, may be arranged to advance material longitudinally of the axes of the rotors 32 and 34 from the inlet 14 to the outlet 16, however, in the structure shown in FIGS. 2 and 3 of the drawings, helic-

ally disposed vanes are used for this purpose, all as will be hereinafter described in detail.

The rotors 32 and 34 counter-rotate in directions, as indicated by arrows A and B in FIG. 3 of the drawings, such that upper portions of the rotors counter-rotate toward each other and, thus, the inlet 14 communicates with the upper portions which counter-rotate toward each other while the outlet 16 communicates with portions of the rotors which counter-rotate away from each other and the helically disposed beaters 44 tend to advance material from the inlet to the outlet, while helically disposed vanes 52 of the preferred structure, tend to helically advance material from the inlet 14 to the outlet 16.

Disposed in the upper portion of the housing 10 is a substantially V-shaped baffle structure 54 having its apex 56 directed downwardly toward the rotors 32 and 34 and directed to a location midway between the axes of these rotors, such that the rotor 34 directs material centrifugally onto one side 57 of the baffle 54 and the rotor 32 directs material onto a side 58 of the baffle 54, these sides being directed downwardly and inwardly so that material thrown from the counter-rotating rotors 32 and 34 passes upwardly and downwardly between rotors, whereupon the material, as it passes in the direction of the arrows A and B and on the sides of the baffle 54 ultimately moves downwardly between the rotors 32 and 34 to an upwardly directed V-shaped in cross-section baffle 60. The material separates at the apex of the baffle 60 and some of it passes, over an arcuate row of grill bars 62 below the rotor 34 and some of the material passes over an arcuate row of grill bars 64 under the rotor 32. The rotors 32 and 34 at the peripheries of the beaters 40 may have a rotating velocity of approximately 3,600 to 4,000 feet per minute. At this speed, centrifugal forces tend to separate motes from cotton fibers, the motes moving between the bars 62 and 64 and downwardly into a trash receiving plenum 18, hereinbefore described.

It will be understood that when the cotton containing motes or other fibers which contain motes pass at high velocity around the rotors 32 and 34, the motes tend to be worked out from the fibers and when separated therefrom, the specific gravity of the motes tends to separate them centrifugally from the fibers, the fibers tend to whirl around the rotors and the motes or foreign matter tend to pass between the bars 62 and 64 and downwardly into the plenum 18.

The vanes 52 are pivotally mounted on a side plate 66 which is removably mounted on the housing 10 near an upper portion thereof adjacent to the rotor 32. Similar vanes 68 are mounted on a removable side plate 70 of the housing 10 near an upper portion of the rotor 34.

Since the vanes 52 and 68 are similar, the vanes 52 will be described in detail.

The side plate 66 is provided with a U-shape flange 72 at its upper edge and a similar U-shaped flange 74 at its lower edge, which flanges 72 and 74 fill their outwardly directed flanges 76 and 78, respectively, of the housing 10.

The vanes 52 are pivotally mounted on pins 80 and these vanes 52 are pivotally adjustable about the axes of these pins 80 by means of a link member 82 provided with pins 84 pivotally connecting the link 82 with normally lower ends of the vanes 52. The link 82 is provided with an end 86 projecting from end of the housing 10 and pivotally connected by means of a pin 88 with an actuating lever 90 disposed on the outside of the plate 66. One end of the lever 90 is pivoted by means of a pin 92 to the plate 66, such that the link 82 may be moved longitudinally of its axis to pivot all of the vanes 52 in unison to adjust their helical angular relationship to the axes of the rotors 32 and 34.

The vanes 68 may be likewise adjustable and may be of the same construction shown in FIGS. 2, 4 and 5 of the drawings.

With reference to FIG. 5 of the drawings, it will be

seen that each vane 52 is provided with a substantially L-shaped cross-section comprising an outwardly directed edge portion 94 which is directed toward the rotor 32, while one leg of the cross-section designated 96 is substantially flat and contiguous with the plate 66. The plate 66 and leg 96 having openings aligned with each other at 98 and the pivot pins 80 are extended therethrough. These pins may be rivets or conventional bolts, as desired.

As shown in FIG. 6 of the drawings, the rotor shafts 36 and 38 carry pulleys 100 and 102, respectively, which are engaged by a belt 104 which also passes over a pulley 106 driven by a motor 108. An idler pulley 110 is also engaged by the belt 104 and this belt 104 extends from an upper arcuate surface of the pulley 100 to a lower arcuate surface of the pulley 102, such as to cause the rotor shafts 36 and 38 to counter-rotate in the directions of the arrows A and B, as shown in FIG. 3 of the drawings.

It will be seen that the trash receiving plenum 18 is provided with an upper edge 112 spaced from a lower edge 114 of the housing 10 and adjustably suspended by bolts 116 so as to permit air to enter the upper portion of the plenum 18 to relieve vacuum in the plenum 18 and merely to permit the blower 26 to pull trash from the conduit 28 at the bottom of the plenum 18. Thus, the vacuum removal of trash from the conduit 28 is prevented from imposing a pressure differential across the bars 62 and 64 and the rotors 32 and 34.

In this manner, the air flows as indicated by arrows C 30 and D in FIGS. 2 and 3, inward around the upper portion of the trash receiving plenum 18 to supply air downwardly through the plenum and trash to carry it into the inlet of the blower 26. Likewise, the outlet 16 is provided with an upper open edge 118 spaced from a lower open edge 120 of the housing 10. Suspension bolts 122 support the outlet 22, such that air is capable of passing inwardly between the upper edge 118 of the outlet 22 and the lower edge 120 of the housing 10, as indicated by arrows E and F in FIGS. 2 and 3 of the drawings. Thus, vacuum created 40 by the blower 26 in a horizontal conduit 123 of the outlet 20 does not act in the housing 10 to create a pressure differential across the bars 62 and 64 and/or the rotors 32 and 34.

In some installations, the machine of the invention may 45 utilize other means for removing the trash from the plenum 18 and the cotton from the outlet 22, as for example, these materials may be carried away by gravity from the machine or by other conveyor means.

It has been found that the machine operates more efficiently 50 without any aerodynamic effects thereon except for those created by the rotors 32 and 34, as hereinbefore described.

In addition to the baffles 56 and 60, hereinbefore described, baffles 125 and 124 are directed inwardly and 55 downwardly from positions above the rotors 32 and 34, so as to direct cotton fibers and motes from the vanes 52 and 68 in downward directions toward the upper areas of the rotors 32 and 34, respectively. These baffles 124 and 125 cooperate with the inverted V-shaped baffle 54, so as to load the central area between the rotors at a location at which the peripheries of the rotors counter-rotate toward each other and this is the area at one end of the housing at which the inlet 14 communicates with the rotors. The baffle 54 and the baffles 124 and 125 terminate at a 60 location 126, as shown in FIG. 2 of the drawings, such as to permit the inlet 14 to deliver fibers and motes to the rotors at said location, the vanes 52 and 68 and/or the beaters 44, shown in FIG. 7, helically advance the material to the ends of the rotors communicating with the outlet 16 at a location designated 128 in FIG. 2 of the drawings, and it will be seen that ends of the bars and the baffles 60 terminate at 130 to permit the outlet 16 to communicate fully with a cross-section of the housing below the rotors 32 and 34.

A baffle 132 is disposed at the location 130 and extends

upward around the cylindrical portions of the rotors 32 so as to provide a cutoff wall for the movement of trash which is disposed to move downwardly between the bars 62 and 64. The baffle 132, as shown in section in FIG. 2 of the drawings, thus extends upward above the bars 62 and 64 to prevent trash from spilling into the area of the outlet 16.

It will be obvious to those skilled in the art that various modifications of the present invention may be resorted to in a manner limited only by a just interpretation of the following claims.

We claim:

1. In a cotton cleaning machine the combination of: a housing; an inlet in said housing and an outlet in said housing; a pair of axially elongated laterally spaced and axially parallel cylindrical rotors having peripheral portions provided with radially extending beater members; a plurality of said members spaced about the periphery of each rotor and said beater members also spaced apart longitudinally of the axis of said rotors; means for counter-rotating said rotors, said inlet in said housing communicating with said rotors near one end of each rotor, said inlet communicating with a space between said rotors at a location in which peripheries of said rotors counter-rotate toward each other, said outlet below said rotors and communicating with said rotors near ends thereof opposite said one end, said outlet communicating with said rotors at a location in which the peripheries of said rotors counter-rotate away from each other; a plurality of elongated laterally spaced grate bars disposed axially parallel to each of said rotors, said grate bars arranged in arcuate rows around lower peripheral portions of said rotors slightly spaced from the ends of said beater members, said grate bars at locations in which peripheries of said rotors counter-rotate away from each other; and a trash receiving plenum communicating with said bars, said bars terminating at said outlet, such that said outlet has unrestricted communication with areas below said rotors.

2. The invention, as defined in claim 1, wherein: a substantially V-shaped in cross-section baffle is provided with an apex portion directed generally toward and spaced from the peripheries of said rotors and substantially aligned midway between the rotary axes of said rotors at said location in which said peripheries counter-rotate toward each other.

3. The invention, as defined in claim 2, wherein: a substantially V-shaped in cross-section baffle is provided

with an apex portion directed toward and spaced from the periphery of said rotors and substantially aligned between the rotary axes of said rotors at said location in which said peripheries counter-rotate away from each other; said last mentioned V-shaped baffle being disposed between said plurality of grate bars.

4. The invention, as defined in claim 1, wherein: means are provided in said housing disposed at a helical angle, such that material traveling around said rotors will be helically advanced from said inlet to said outlet.

5. The invention, as defined in claim 4, wherein: said material advancing means includes a plurality of angular baffles in said housing, said baffles spaced longitudinally relatively to said rotor axes and having vane portions directed in a generally helical direction with respect to said rotor.

6. The invention, as defined in claim 5, wherein: said baffles are pivotally mounted in said housing and adapted to be pivoted to vary the angle of said helical direction; and link means communicating with the outside of said housing and pivotally interconnecting said baffles to concurrently adjust them angularly in said helical direction.

7. The invention, as defined in claim 4, wherein: said material advancing means comprises said rotor beaters disposed at a substantially helical angle relative to the rotational axes of said rotors.

8. The invention, as defined in claim 1, wherein: the said axes of said rotors are horizontally disposed, said inlet is above said rotors, said outlet is below said rotors; and said trash receiving plenum is below said grate bars.

9. The invention, as defined in claim 1, wherein: means is provided for preventing a substantial aerodynamic effect around said rotors and said bars except that created by rotation of said rotors.
